UNITED STATES PATENT OFFICE.

ARTHUR R. FUGINA, OF LOUISVILLE, KENTUCKY.

RENITENT RAILWAY-RAIL SUPPORT.

1,329,077.

Specification of Letters Patent. Patented Jan. 27, 1920.

Application filed September 9, 1918. Serial No. 253,300.

To all whom it may concern:

Be it known that I, ARTHUR R. FUGINA, a citizen of the United States, residing in the city of Louisville, county of Jefferson, 5 and State of Kentucky, have invented a new and useful Improvement in Renitent Railway-Rail Supports, of which the following is a specification.

This invention relates to means adapted 10 to permit of a degree of depression between certain unyielding points in a railway rail.

In railway signal service it is necessary 15 that a moving train, shall as it passes selected points actuate mechanism which is adapted to transmit signals. Difficulty has been experienced in providing mechanism that will "stand up" under the severe strain imposed upon it by the hammer like blows delivered by rapidly moving trains. Applicant proposes to actuate such mechanism by 20 a vertical deflection of the rail, caused by a passing train. As the deflection required is slight and occurs progressively as the train moves toward the center of the deflectable zone, or section, of rail, the transmitting mechanism will be actuated without a shock.

An object of this invention is to provide 25 a yielding support adapted to be placed between a rail and a cross-tie, or sleeper.

Another object is to provide an assemblage, comprising a tie-plate and an associated renitent element which may be installed, under a railway rail, without 30 entailing additional labor over that required for an ordinary tie-plate.

A further object is to provide a rail support of the character described, which will be economical in construction, durable in 35 service, and which will be servicable under all climatic conditions.

The invention may be understood from a consideration of the following detailed description taken in connection with the accompanying drawing which forms a part 40 of this specification, with the understanding however that while the drawing shows a practical embodiment of the invention, the latter is by no means limited to exact conformity therewith, but may be embodied in 45 any other form which may come within the scope of the claim appended hereunto.

In the drawing, herein similar reference characters designate like parts in the several views, Figure 1, is a top plan view of an embodiment of the invention as installed under a rail; and Fig. 2, a side elevation of same.

As illustrated the invention comprises a base or plate —10— of usual, or any desired construction, such as is customary to place between a rail —11— and a cross tie, or sleeper —12— for the purpose of providing a broader bearing surface on the tie. The plate is provided with a plurality 60 of perforations —13— through which securing means may be driven into the cross tie. A renitent element —15— is so connected with the plate that in functioning it may move freely relative thereto but may not 65 become separated therefrom in handling or transporting. In the embodiment herewith illustrated the renitent element comprises a strip of steel spring which is of less width than the tie plate, and is arched upward in 70 the center as at —16—. The height of the arch above the tie-plate is preferably equal to the movement desired, the intent being that the spring plate shall flatten out on the tie-plate at each complete depression. The 75 spring plate has a slight upward curve —17— at each end which permits it to slide freely on the tie-plate. The spring plate may be connected with the tie-plate by any suitable means, a preferred method being 80 by the use of button-head rivets —18—, the bodies of which are received in slots —19—, which extend inward from the ends of the plates, the heads of the rivets bear upon the upper surface of the spring plate and 85 are riveted in counter-sunk depressions on the underside of the tie-plate, leaving the tie-plate smooth on its underside.

To install the device, a recess is cut in the tie, of suitable dimensions, the base-plate 90 placed therein and spiked down in the customary manner. Spikes —23—, or other securing means are then passed through perforations —24— in the tie-plate which are positioned in proximity to the edge of the 95 rail and driven in until the heads thereof impinge upon the flanges of the rail and the tie is drawn up until the crown of the arch 100 contacts with the under surface of the

rail, ballast is then tamped under the ties, in the usual manner, to level up the rail. Actual service, extending through the winter months has demonstrated that this device will clear itself of any substance, including ice, that may get between the two plates.

Having thus described my invention so that any one skilled in the art pertaining

thereto can make and use the same, what is claimed as new is—

In a device as characterized, a base, an elongated curved elastic plate having slots extended in from the ends thereof, retaining means extended through said slots and secured to the base.

ARTHUR R. FUGINA.
